D. D. Rankin

UNITED STATES PATENT OFFICE.

DAVID RANKIN, OF AUGUSTA COUNTY, VIRGINIA.

METHOD OF APPLYING WATER TO CUNEIFORM BUCKETS OF FLUTTER-WHEELS.

Specification forming part of Letters Patent No. 11,255, dated July 11, 1854; Reissued September 26, 1854, No. 277.

To all whom it may concern:

Be it known that I, DAVID RANKIN, of 5
Augusta county, in the State of Virginia,
have invented certain new and useful Im-
provements in the Construction and Ar-
rangement of Chutes and Flutter Water-
Wheels; and I do hereby declare the follow-
ing to be a full, clear, and exact description
of the same, reference being had to the ac-
companying drawings, making a part there-
of, and which represent a side view of the
flutter-wheel and a section through the
forebay.

The nature of my invention relates to the
cuneiform shape of the floats or buckets and
their arrangement with regard to an ec-
centric water-way or chute board, so that
the water shall act on at least three buckets,
in the proportions of about thirty-three
20 per cent. on the first, sixty-six on the second,
and thirty-three on the third or last bucket,
which should but barely escape the bottom
of the chute board, at the point where the
power of the water is exhausted.

25 To enable others skilled in the art to make
and use my invention, I will proceed to de-
scribe the same with reference to the draw-
ings.

30 S, is the shaft of the wheel, which may be
of wood or iron or both, as may be found
essential, and which is provided with any
suitable number of radial arms, for carrying
the floats or buckets F, F, &c.

The floats or buckets F, are cuneiform or
35 wedge-shaped, and so let into the ends of
the arms, that their inclined sides which re-
ceive the water shall stand as nearly at
right angles to the column of descending
water as can be safely done, and prevent the
40 water from running to the center of the
wheel.

In the general construction of flutter
wheels and their chutes, heretofore, the fore-
bay overhung the wheel, and the water-way
45 was concentric with the wheel. In this mode
of construction, the bucket on the horizontal
arm closed up the water-way, and destroyed

the action of the water on the bucket in
advance of it. I make my chute board S, B,
eccentric with the wheel, so that the bucket 50
on the horizontal arm (F') shall take about
33 per cent. of the volume of water, the
one in advance of this (F²) taking about
33 per cent., and the next in advance (F³)
taking the remaining 33 per cent. of the 55
volume. I find that this arrangement, and
these proportions produce the most desir-
able results. The line a, b, drawn from the
center of the wheel through the corner of
the bucket will represent its position on the 60
arm and how they are set thereon.

P, represents the forebay or penstock and
B the breast board. The point f, of the
breast board projects slightly below the bot-
tom of the penstock, e, q, representing the 65
line of said bottom. The chute board may
be perpendicular from e to d, but from d,
to its extreme end it curves around ec-
centrically in relation to the wheel until at a
70 point about perpendicular from the center
of the wheel the last float or bucket acting,
shall just escape it in passing.

The proportions of the wheel generally,
and of the chute, may be varied to suit the
head and fall of water, the rules for which 75
are laid down in the elementary books on
this subject, and need not here be repeated.

Having thus fully described the nature
of my invention I would state that I do
not claim a wedge shaped bucket, or an ec- 80
centric water-way, when used separately;
but—

What I do claim therein as new, and de-
sire to secure by Letters Patent, is—

So arranging cuneiform buckets upon the 85
radial arms of flutter wheels, that in passing
through an eccentrically formed water-way,
three buckets shall receive the volume of
water in about the proportions herein de-
scribed and represented.

DAVID RANKIN.
